[57] CLAIM

The ornamental design for a steering column mounted control stalk, as shown.

DESCRIPTION

FIG. 1 is a front side elevational view of a steering column mounted control stalk embodying my design;
FIG. 2 is a top plan view thereof;
FIG. 3 is a right end elevational view thereof;
FIG. 4 is a rear side elevational view thereof;
FIG. 5 is a bottom plan view thereof; and
FIG. 6 is a left end elevational view thereof.

—FIG. 1

—FIG. 2

—FIG. 3

FIG. 4

FIG. 5

FIG. 6
